UNITED STATES PATENT OFFICE.

JAMES DANIEL, OF CARROLLTON, OHIO; J. C. OGLEVEE ADMINISTRATOR
OF SAID JAMES DANIEL, DECEASED.

DIE FOR MAKING ROOFING-TILES.

SPECIFICATION forming part of Letters Patent No. 726,144, dated April 21, 1903.

Application filed August 11, 1902. Serial No. 119,360. (No model.)

To all whom it may concern:

Be it known that I, JAMES DANIEL, a citizen of the United States, residing at Carrollton, in the county of Carroll, State of Ohio, ⁵ have invented an Improved Die for Making Roofing-Tiles, of which the following is a specification.

My invention is a die for the production of clay roofing-tile, the same to be attached to ¹⁰ any machine used for making drain-tile and operated in the same way, producing a tube of clay having eight plain sides—four sides of any desired width for a shingle and the other four sides of such width that when divided ¹⁵ in center it will leave a flange that will keep water from flowing over the side of the shingle—core of said die to be of such size as to make the inside and outside of each shingle the same width. The core has four cutting- ²⁰ points that cut part way through the clay, the points to be adjustable as to depth of cut.

One advantage of this die is that when I cut a shingle length I cut four shingles, the same to be dried and burned before breaking ²⁵ apart. This prevents warping in the burn.

Finished shingles are laid in roof alternately flange up and flange down.

Said die is illustrated in the accompanying drawing.

³⁰ A represents core of die made of metal.
B B B represent tubes of clay.

C represents outside portion of die, also made of metal.

Numerals 1 2 3 4 represent clay shingles.

³⁵ Numeral 5 indicates flanges on shingle after being broken apart at cutting-points.

Numeral 6 indicates cutting-points adjustable by set-screws at 7.

⁴⁰ 8 represents a bracket-bolt. Tube of clay at sides marked 5 is thinner than at sides marked 1 2 3 4, which requires back of core to be made with deeper bevel at 5 than at 1 2 3 4.

What I claim as my invention, and desire ⁴⁵ to secure by Letters Patent, is—

1. A die for molding clay roofing-tiles having inclined side flanges, said die comprising an outer member having an opening of polygonal form, with certain of its sides at right

angles to each other and its intermediate sides ⁵⁰ disposed obliquely with reference to the right-angled sides, and an inner member corresponding in exterior form to said opening and of such size as to lie within said opening, but out of contact with the sides thereof, the ⁵⁵ spaces between the oblique-angled sides of said opening and said inner member being narrower than those between the right-angled sides thereof, and cutting devices disposed in said oblique-angled narrowed spaces for the ⁶⁰ purpose set forth, substantially as described.

2. A die for molding clay roofing-tiles, having angled side flanges, said die comprising an outer member having an opening of polygonal form with certain of its sides at right ⁶⁵ angles to each other and its intermediate sides disposed obliquely with reference to the right-angled sides, and an inner member corresponding in exterior form to said opening, lying within and having its sides spaced from ⁷⁰ those of the opening, the opposing sides of the opening and the inner member being parallel, and cutting devices projecting into the spaces between the oblique-angled sides of the said opening and said inner member, substantially as described.

3. A die for molding clay roofing-tiles, having angled side flanges, said die comprising an outer member having an opening of polygonal form with certain of its sides at right ⁸⁰ angles to each other and its intermediate sides disposed obliquely with reference to the right-angled sides, and an inner member corresponding in exterior form to said opening, lying within and having its sides spaced from ⁸⁵ those of the opening, the opposing sides of the opening and the inner member being parallel, and adjustable cutting devices projecting into the spaces between the oblique-angled sides of the said opening and said inner ⁹⁰ member, substantially as described.

In testimony whereof I have signed my name to this specification in the presence of two subscribing witnesses.

JAMES DANIEL.
